HARRY C. HACKETT, OF KANSAS CITY, MISSOURI, ASSIGNOR OF TWO-THIRDS TO
GEORGE W. ANDERSON AND JOSEPH P. FITZGERALD, BOTH OF KANSAS CITY,
MISSOURI.

SHIPPING-CASE FOR EGGS.

1,153,620.

Specification of Letters Patent. Patented Sept. 14, 1915.

Application filed January 22, 1914. Serial No. 813,669.

To all whom it may concern:

Be it known that I, HARRY C. HACKETT, a citizen of the United States, residing at Kansas City, in the county of Jackson and 5 State of Missouri, have invented a certain new and useful Improvement in Shipping-Cases for Eggs, of which the following is a specification.

My invention relates to improvements in 10 shipping cases for eggs.

The object of my invention is to provide a novel shipping case in which eggs may be safely transported by express or parcel post, and which does not require care in 15 handling to prevent breakage of the eggs.

A further object of my invention is to provide a shipping case which will meet the requirements of the postal regulations, which is cheaply made, which may be quickly 20 filled or emptied, which is extremely light and strong, and which is of compact form.

The novel features of my invention are hereinafter fully described and claimed.

In the accompanying drawings, which 25 illustrate the preferred embodiment of my invention, Figure 1 is a perspective view of my improved shipping case, partly broken away, and with the cover shown in the open position. Fig. 2 is a transverse vertical sectional view of the case, showing the cover in the closed position and eggs mounted in the case. Fig. 3 is a plan view of the inner container box. Fig. 4 is a plan view of the outer container box partly broken away.

30 Similar reference characters designate similar parts in the different views.

1 designates the outer casing comprising preferably a box and cover of rectangular form made from a single piece of cardboard 40 comprising three layers, the middle one of which is corrugated. The cover 2 of the outer casing is hinged at one edge to the body of the casing and has hinged to its other edges respectively three flaps 3 which, 45 when the cover is in the closed position, shown in Fig. 2, embrace respectively the adjacent three sides of the body of the casing.

4 designates the inner container box, shown in Fig. 3, also preferably composed 50 of corrugated card-board and which is adapted to be inverted and slidably and removably fitted in the outer container box 5, shown in Fig. 4, the latter box being adapted to be slidably and removably mounted in the 55 casing 1, as shown in Fig. 1.

In its operative position, the inner container box 4 is inverted as shown in Fig. 1. Secured to the bottom of each of the boxes 4 and 5 upon the inner side thereof are a plurality of vertical tubular egg containers 60 6, the containers in one box being disposed so as to respectively longitudinally aline with the containers in the other box, as is shown in Fig. 1.

Each of the containers 6 consists preferably of a card board tube having double walls, the inner one of which is preferably corrugated, as shown in the drawing. Each container 6 is provided adjacent to the end, which is secured to the bottom of the box 70 which contains it, with a yielding seat comprising preferably a cup-shaped member 7 having a flexible end provided with a central hole 8, which is adapted to receive one end of an egg which is held in the container. 75 The other end of the egg is mounted in a similar hole provided in a similar cup-shaped seat 7, which is provided in the container 6 supported by the opposite box.

The depth of each of the boxes 4 and 5 is 80 such, preferably, that when the eggs, designated by 9 are mounted in the containers, the adjacent edges of the boxes 4 and 5 will be separated from each other, so that the eggs will wholly support the box which 85 chances to be at the top.

In the operation of my invention, the eggs may first be placed in the containers 6 of the box 4, this being the shallow box, after which the larger and deeper box 5 is inverted and 90 then slipped over the smaller box 4 to a position in which the upper ends of the eggs will enter the holes 8 of the containers 6 which are held in the box 5. The box 5, with the box 4 held therein, is then slipped 95 into the casing 1, with either one of the boxes in the uppermost position, as may be convenient for the operator. In Fig. 1, the smaller box 4 is the one which is shown in the upper and inverted position. The 100 cover 2 is then swung to the closed position shown in Fig. 2, after which the flaps 3 are swung against the adjacent sides of the body of the casing 1, in which position they may be secured by any suitable means, such as a 105 cord, not shown, which may be tied around the casing.

When the eggs are mounted in the containers in the manner which I have hereinbefore described, they will be wholly sup- 110

ported adjacent to their ends by the flexible bottoms of the cup-shaped seats 7, and when so supported, the casing may be very roughly handled without danger of breaking the 5 eggs, and in case that any of the eggs should be broken, none of the material can escape from the casing.

By having the cup-shaped seats 7 yielding and resilient, as they are, said seats which 10 support the longer eggs, will yield, when the casing has been closed and tied up, sufficiently to permit the smaller eggs to have their ends engaged and be supported by the seats which are adjacent to their ends. To 15 enable this to be accomplished, the length of the containers 6 is such that when filled with eggs of the ordinary run and size, the ends of the containers which are in and are secured to the box 4, will be separated and out 20 of contact from the adjacent ends of the containers 6 which are secured to the box 5. The eggs will thus be firmly held at their 25 ends by yielding supports, and will have their ends spaced apart from the bottoms of the boxes 4 and 5, the depth of the cup-shaped seats 7, and the diameters of the holes 8 being such that a space will be provided between the extreme ends of the eggs and the bottoms of the boxes 4 and 5.

I do not limit my invention to the structure which I have shown and described, as many modifications, within the scope of the appended claims, may be made without departing from the spirit of my invention.

Having thus described my invention, what 35 I claim and desire to secure by Letters Patent, is:—

In a shipping case for eggs, two boxes, one removably and slidably mounted in the other, and two sets of tubular containers respectively mounted in said boxes and secured to the bottoms thereof, said sets of containers being respectively provided with yielding seats having holes adapted to respectively receive the ends of eggs held in 45 said containers, the containers of one set being disposed respectively in longitudinal alinement, with the containers of the other set, the containers of opposite sets being arranged in pairs, each pair being adapted to 50 contain an egg.

In testimony whereof I have signed this specification in presence of two subscribing witnesses.

HARRY C. HACKETT.
